H. L. HUBBARD

AUTOMOBILE HEATER

Filed Feb. 8, 1926

UNITED STATES PATENT OFFICE.

HENRY L. HUBBARD, OF CLEVELAND, OHIO.

AUTOMOBILE HEATER.

Application filed February 8, 1926. Serial No. 86,886.

My present invention relates generally to automobile heaters, and more particularly to that type of heater wherein the heating elements are disposed below a grate in the bottom of an automobile, and in which the heating elements, usually heat radiating tubes and the like, are fed through an adjacent valve structure from the exhaust pipe.

Heaters of the above type commonly include a pan which extends beneath the heating tubes or other elements below the grate, and great disadvantage has been experienced due to the fact that dirt and foreign matter of various character finds its way down through the grate and into the pan with no means of clearing the pan of such dirt and accumulations except by removing the pan. Another disadvantage of the type of heater fed from the exhaust pipe, is the susceptibility to leakage, and it is a primary object of my present invention to provide an automobile heater which will eliminate the above disadvantages, and which may thus be used with greater satisfaction and efficiency.

In the accompanying drawing which illustrates my present invention and forms part of this specification:—

Figure 1 is a sectional perspective view illustrating the practical application of my invention;

Figures 2 and 3 are vertical transverse sections taken respectively on lines 2—2 and 3—3 of Fig. 1;

Figure 4 is a horizontal section taken substantially on line 4—4 of Fig. 2, and,

Figure 5 is a detail vertical section through a portion of the valve adjusting connection.

Referring now to these figures, and particularly to Fig. 1, I have shown certain portions of an automobile, including a floor 10, and an exhaust pipe 11 below the floor, the latter of which is apertured as indicated at 12, in Fig. 2, within a valve casing which surrounds the same and encloses a valve 14 controlled in accordance with my invention by virtue of its external adjusting lever 15 shifted in one direction by virtue of a spring 16. Rising from the valve casing 13 is a flexible pipe 17 whose lower end is secured in a permanent non-leaking manner, as by means of solder and the like, to the upstanding neck 18 of the valve casing, and whose upper end is similarly connected in a permanent non-leaking manner, as by means of solder within the lower end of a tubular

fitting 19, having a flange 20 at its upper end.

I have also shown in Figs. 1, 2 and 3, an upper grate 21 and below this grate a series 60 of heating elements including parallel tubes 22, preferably provided with heat radiating members, as for instance the circular fins 23. These heating tubes extend at one end from a header 24, in the lower portion of the latter of which approximately at its center, is an inlet opening 25. This header 24 is also preferably provided across its top with heating radiating ribs, and with a depending boss 27 around the lower portion of its lower 70 opening, and the header is also provided therein with webs or baffle plates 28 depending from the top thereof between the adjacent ends of the several heating tubes 22, so as to divide the hot gases rising into the 75 header and insure substantially equal distribution of the same to the heating tubes. At their opposite ends, the tubes 22 may outlet in any suitable manner as for instance by casting the same integral with an outlet 80 header 22^a, as shown in Figure 4, having an exhaust outlet pipe 22^b leading therefrom. As the hot gases rise in the flexible pipe 17, the same will be discharged directly upward and against the top wall of the central portion of the header 24, and will bank up within this portion of the latter in a manner to cause a back pressure tending to force relatively large proportions of the hot gases under the lower edges of the webs or baffles 90 28 for a more equal distribution of the hot gases to all of the several compartments of the header 24, and consequently to the several heating tubes 22.

Secured with its upper surrounding edge 95 beneath the anchored and surrounding edge of the grate 21, is a pan 30, which extends beneath the several heating tubes 22, and the header 24, and is pierced at one side in alignment with the lower opening 25 of the header, and the depending tubular fitting 19, the flange 20 of the latter being securely fastened to the lower boss 27 of the header by clamping screws 31, at spaced points around the flange so as to thus complete a non-leaking joint between the header 24 and the tubular fitting 19, through that portion of the pan 30 immediately around its beforementioned opening.

The entire central portion of the pan 30 110 is open and this opening is normally covered by a drop door 32 which is hinged at

one side to the pan as at 33, so that its free edge may be dropped from the normal horizontal position shown in full lines in Fig. 3 to the vertical open position shown in dotted lines in the same figure. Adjacent to its hinged side the drop door 32 has a curved arm 34 normally upstanding within the pan and to which one end of a Bowden cable 35 is attached. This cable 35 passes across the drop door and upwardly within one side of the pan, through a curved guide tube 35^a, and the upper end of the cable is secured to a handle or knob 36 normally disposed within a recess in the surface of the grate 21, so that the handle or knob 36 is, in its lower position, this being the normal position with the drop door 32 closed, flush with the surface of the grate so as not to interfere with the passengers within the vehicle. It is obviously only necessary to grasp the knob or handle 36 and pull the same upwardly in order to swing the door to its lower vertical open position, the door being normally held in closed position by flat springs 37.

The handle 15 of the valve, which as above stated is moved in one direction by the spring 16, is likewise connected at its free end to one end of a Bowden cable 38 extending through a guide tube 39 and upwardly through a floor plate 40, that portion of the wire extending through floor plate 40 being threaded for the reception of a nut 41, adjustable on the wire cable and adapted to rest on the floor plate 40 to control the position of the valve 14. The upper extremity of this cable 38 has a knob or head 42, and this valve control is as shown in Figure 1, preferably located immediately adjacent to the seat 43 of the vehicle so as to be as nearly out of the way as possible.

It is obvious from the foregoing that by

the use of the drop door 32, which may be easily and quickly manipulated, when desired, the pan may be maintained in a 45 cleanly condition and provision made for the discharge of dirt and other refuse at all times, and it is also obvious that by virtue of the header 24, and its internal baffles or webs 28 even distribution of the source of 50 heat, the exhaust gases, is insured among the several heating tubes or pipes 22. It is also obvious that by the utilization of the flexible upright tube 17 whose ends may be permanently connected in a non-leaking 55 manner to the tubular fitting 19 of the valve casing 13, as well as the connection of the upper flanged end of the fitting 19 through the pan 30 with the lower bodies of the header, I provide against all danger of 60 leaks, one of the greatest disadvantages of all heaters utilizing as a heating medium, the exhaust gases of the automobile engine. It is also obvious that by virtue of the means provided by my invention for the adjustment of the valve 14, the degree of heat 65 may be readily controlled and easily maintained at the desired regulation.

I claim:—

An automobile heater including an upper 70 grate, heating elements below the grate including a series of tubes, a header with which the tubes communicate at one end, having a lower intake opening, a pipe for supplying heated gases having connection 75 with the lower opening of the header, and a series of baffle members depending in the header and converging toward its intake opening from points between the several 80 heating tubes, whereby to insure substantially uniform distribution of the heat to the said tubes.

HENRY L. HUBBARD.
